UNITED STATES PATENT OFFICE.

SEYMOUR L. SMITH, OF BROOKLYN, NEW YORK.

CONTROLLING SWITCH.

Application filed March 30, 1926. Serial No. 98,569.

This invention relates to switches and more particularly to an electric controlling switch for use in connection with vehicle-carried traffic signal devices of the type which includes "Stop," "Slow," "Right," and "Left" indicating signals.

The principal or outstanding object of the present invention is to provide a controlling switch of the character set forth having a single manipulating handle by means of which the signaling circuit may be controlled to display the signals enumerated either singly or in combination, whereby the operator of a vehicle may unmistakably signal in ample time to the drivers of other vehicles, his intention to slow down, stop, or make a turn.

The invention further comprehends a controlling switch including indicating means simultaneously operable with the switch for indicating to the operator the signals which may be given.

The invention furthermore contemplates a controlling switch for signaling circuits of the character set forth which is comparatively simple, compact, and durable in its construction and mode of operation, inexpensive to manufacture, and which is thoroughly reliable and highly efficient in its purpose.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a perspective view of the switch in applied position on the steering column of a motor vehicle;

Fig. 2 is a plan view of the switch illustrating the same in its neutral position;

Fig. 3 is an enlarged sectional view through the switch casing illustrating the switch proper in side elevation;

Fig. 4 is a sectional view taken approximately on the line 4—4 of Fig. 3, illustrating the clamping means for attaching the switch to the steering column;

Fig. 5 is an enlarged fragmentary sectional view through the switch proper illustrating the same in neutral position;

Fig. 6 is a similar horizontal sectional view taken approximately on the line 6—6 of Fig. 5;

Fig. 7 is a detail transverse sectional view taken approximately on the line 7—7 of Fig. 5;

Fig. 8 is a similar view taken approximately on the line 8—8 of Fig. 5;

Fig. 9 is a fragmentary plan view of the switch with the casing top removed;

Figs. 10 to 17, inclusive, are fragmentary, diagrammatical plan views illustrating the various positions of the switch handle and the shutters of the indicating means;

Fig. 18 is a view of the wiring diagram.

Referring to the drawings by characters of reference, the switch includes a casing or housing body 20 which is formed with an angular extension 21, the free terminal of which has mounted therein a sliding block 22 to which the opposite ends of a looped strap 23 is to be connected, said strap cooperating with the concave face 24 of the extension terminal to constitute means for embracing and clamping the steering column 25 of a vehicle, whereby the switch casing or housing will be properly supported in juxtaposition to the steering wheel 26. The block 22 is moved and retained by means of threaded stems 27 having kerfed ends which are exposed through openings 28 in the casing to adjust the strap to various sizes of steering columns.

The switch proper includes a stationary section comprising a block 30 having vertically spaced upper and lower plates 31 and 32 of an insulating material; the switch proper further includes a laterally swingable section which comprises a block 33 of a conducting material having laterally spaced plates 34 and 35 of an insulating material secured thereto. The block 33 of the movable section is connected with the

plates 31 and 32 of the stationary section for lateral swinging movements by a pivot 36 which is in the nature of a screw or bolt extending through the alined apertures in 5 the plates 31 and 32 and the block 33, which bolt is held in place by a retaining nut 37. The switch proper further includes a vertically swingable section which consists of a block 38 of a conducting material positioned between the laterally spaced vertical plates 34 and 35 of the first-mentioned movable section, which will hereinafter be termed the "intermediate section" and which is pivotally associated therewith by a transverse bolt 39 extending through alined apertures in the plates 34 and 35 and the block 38. The block 38 is formed with a threaded outwardly projecting stem 40 which carries an internally threaded handle 41 of an insulating material. The stationary section has secured thereto two sets or pairs of spaced or spring contact elements 42 and 43, and 44 and 45, which are mounted and secured to the plates by bolts 46 which also constitute binding posts. A bridge piece 47 constituting a projection of the block 33 of the intermediate section is capable of being selectively moved to projecting position between the contacts 42 and 43, or the contacts 44 and 45, upon lateral swinging movement of the intermediate section, or disposed in a neutral non-bridging position as illustrated in Fig. 7, when said section is in a neutral position.

35 In order to maintain the intermediate section in any one of its three positions, the block 33 has on its opposite side faces, rack members 48 formed with teeth with which spring detents 49 engage, the detents being carried by the vertical partition wall 50 of the stationary member. The intermediate section has secured thereto two sets or pairs of spaced spring contact elements 51 and 52, and 53 and 54, which are mounted, and 45 secured to the plates by bolts 55 which also constitute binding posts. A bridge piece 56 constituting a projection of the block 38 of the outer movable section is capable of being selectively moved to projecting positions between the contacts 51 and 52, or the contacts 53 and 54, upon vertical swinging movement of the outer section on manipulation of the handle 41, or disposed in a neutral non-bridging position as illustrated 50 in Fig. 8, when said section is in a neutral position.

In order to retain the outer section in any one of its three positions, the block 38 has on its opposite upper and lower faces, rack 55 members 57 formed with teeth with which spring detents 58 engage, the detents being carried by the block 33 of the intermediate section.

The handle 41 extends through an opening 59 in the casing or housing 20, so that the

same is disposed immediately under the rim of the steering wheel 26 in a convenient position to be manipulated by the driver of the vehicle without removing his hand from the steering wheel.

The switch is especially designed for use in connection with a signal circuit which includes a "Right" directional indicating signal 60, a "Left" directional indicating signal 61, a "Stop" signal 62 and a "Slow" signal 63. The circuit is preferably of the grounded one-wire type in which the "Right" signal 60 is connected by a circuit wire 64 with the contact element 42; the "Left" signal connected with the contact element 44 by a circuit wire 65; the "Stop" signal 62 connected by a circuit wire 66 with the contact element 54, and the "Slow" signal 63 connected by a circuit wire 67 with the contact element 52. The remaining contact elements of each set or pair are connected in parallel with one pole of a battery or source of supply 68 by circuit wires 69, 70, 71 and 72, which respectively lead from the contacts 43, 45, 53 and 51 to a common circuit wire 73. The opposite pole of the battery or source of supply 68, is grounded as illustrated at 74, while the opposite pole of each signal 60, 61, 62 and 63 is connected by a common wire 75 to a ground 76. Under this arrangement, it is obvious that with the switch in a neutral position any one of the signals may be selectively actuated singly by moving the handle 41 laterally, which, it is obvious, will move the outer and intermediate sections of the switch laterally to cause the bridge piece 47 to assume a projecting relation either with the spaced contacts 42 and 43, or spaced contacts 44 and 45. In the first instance where the bridge piece is engaged between the contacts 42 and 43, the current will flow from one pole of the battery through the common circuit wire 73 to the circuit wire 69, thence through the contact 43, bridge piece 47, contact 42, circuit wire 64 to the "Right" signal 60, through which the current will flow to the common ground wire 75, ground 76, thence through the battery ground 74 to the opposite pole of the battery for energizing or actuating the "Right" signal 60. It is obvious that movement of the handle and the switch elements in the opposite lateral direction will dispose the bridge piece 47 between the contacts 44 and 45 to actuate the "Left" signal 61. With the switch in neutral position, upward movement of the handle 41 will dispose the bridge piece 56 between the contacts 51 and 52, in which instance only a movement of the outer section of the switch is effected. This will close the circuit to the "Slow" signal, due to the fact that the current will flow from one pole of the battery or source of supply 68, through the common circuit wire 73, the cir-

cuit wire 72, the contact 51, the bridge piece 56, the contact 52, the circuit wire 67, the "Slow" signal 63 to energize the same, thence through the common ground wire 75, the ground 76, and the battery ground 74, to the opposite pole of the battery. A downward swinging movement of the handle 41 will obviously engage the bridge piece 56 between the contact elements 53 and 54 closing the circuit of the "Stop" signal 62 and energizing or actuating the same.

From the foregoing it will be further obvious that a movement of the handle 41 laterally and vertically will effect a closing of the circuit to a combination of signals: for instance, if the handle 41 is swung to the right and upwardly, at the same time the bridge piece 47 will engage between the contacts 42 and 43 and the bridge piece 56 between the contacts 51 and 52, thus energizing or actuating both the "Right" signal and "Slow" signal, due to the fact that the circuits will be closed simultaneously to said signal devices. If the handle is moved to the right and downwardly, the bridge pieces 47 and 56 will be respectively engaged between the contacts 42 and 43 and the contacts 53 and 54, thereby displaying the "Right" and "Stop" signals. On the contrary, if the handle 41 is swung to the left and upwardly, the bridge pieces 47 and 56 will be engaged between the contacts 44 and 45 and the contacts 51 and 52, displaying the "Left" and "Slow" signals, whereas if the handle is swung to the left and downwardly, the bridge pieces 47 and 56 will be engaged between the contact elements 44 and 45, and 53 and 54, indicating "Stop" and a contemplated "left" turn.

In order that the driver may be afforded visual indication of the proper working of the signals and in order that he may have a check upon the position of the handle and the signal or signals which are being displayed, the present invention embodies an indicating means for this purpose, which includes a lamp 77 arranged in the lower part of the housing 20, in a socket 78 arranged in series in the signal circuit in any desired manner such as illustrated in Fig. 18. It is obvious that the lamp 77 is de-energized when both of the bridge pieces 47 and 56 are in a neutral non-bridging position, but that such lamp will be energized if either of the bridge pieces is moved to bridging relation with either of its set or pair of spaced contacts 42 and 43, 44 and 45, 51 and 52, or 53 and 54. From this it will be observed that the lamp 77 is energized or lighted when any one of the signals or any combination of signals is energized, so that the interior of the casing 20 is illuminated, and due to the fact that the same is arranged in series with any signal which is being energized, failure of the signals to light will prevent lighting of

the pilot light and will notify the driver that the signals are not operating properly.

In order that the operator may distinguish which one or combination of signals is lighted or displayed, the portion 82 of the casing cover which overlies the main portion of the body or casing 20, is formed with window openings 83, 84, 85 and 86, respectively corresponding to the "Right" signal 60, the "Left" signal 61, the "Stop" signal 62 and the "Slow" signal 63, either by suitable indicia, symbols, or any other means. A pair of shutters 87 and 88 are employed and are arranged within the casing to underlie the window openings, the same being disposed when the switch is in neutral position to cover the window openings and designed to be moved relatively when the switch is manipulated to uncover one or a combination of the window openings corresponding to the signal being displayed so that the lamp 77 illuminating the inside of the casing will render visible the uncovered window opening or openings. This is accomplished by mounting the arm 89 of the shutter 87 on a pivot pin 90, which projects upwardly from the upper plate 31 of the stationary section of the switch and forming the free arm terminal with a notch 91 within which an actuating element, such as a screw head 92 engages, which element or screw is carried by and projects upwardly from the block 33 of the intermediate switch section. Under this arrangement, the swinging of the handle and intermediate switch section laterally will, due to the engagement of the element or screw 92 with the notched free terminal of the arm, effect lateral swinging movements of the shutter 87 to uncover, respectively, the window openings 83 and 84. For example, when the handle 41 and intermediate switch element is swung rearwardly, as indicated in Fig. 10, to display on the signaling device a left turn, the shutter 87 will be swung forwardly to uncover the window opening 84 which simulates and indicates to the driver that the switch is set and that the signals are operating to display a left turn. On the other hand, when the handle 41 is swung forwardly, as illustrated in Fig. 11, the shutter 87 uncovers the window opening 83 to indicate to the driver that the switch is set and that the signals are displaying a right turn. In either of these positions, the shutter 88 which underlies the window openings 85 and 86, will not be moved sufficiently to uncover either of said window openings. The shutter 88, however, is provided with an arm 93 which is fulcrumed on a bracket 94 carried by the plate 35 of the intermediate switch section, while said shutter 88 is further provided with a transversely slotted actuator arm 95, in which an upwardly projecting actuator pin 96 is received, said actu-

ator pin being carried by the block 38 on the outer switch section. Under this arrangement when the outer switch section is moved vertically with the manipulating handle 41, the engagement of the pin 96 in the slotted arm 93 due to its relative swinging movement with respect to the pivotal point of the shutter 88, will cause said shutter to swing forwardly or rearwardly a sufficient distance 10 to selectively uncover the window openings 85 and 86. For example, when the switch arm is swung upwardly as illustrated in Fig. 12, the shutter 88 will be swung rearwardly to the right to uncover the window opening 86 which indicates an arrangement of the switch and a display of the "Slow" signal 63. When the manipulating handle 41 is swung downwardly as illustrated in Fig. 13, the shutter 88 is swung forwardly 20 to uncover the window opening 85, which corresponds to the "Stop" signal 62 and indicates a condition of the switch to display a "Stop" signal. It follows that an upward movement and shifting of the manipulating handle 41 rearwardly, as illustrated in Fig. 14, indicates to the driver that the switch is "set" and the signal is displaying a combination of "Left" and "Slow" signals; when the handle is shifted rearwardly and moved 25 downwardly, as illustrated in Fig. 15, that a "Left" and "Stop" signal combination is being displayed; when the handle is shifted forwardly and up, as illustrated in Fig. 16, that a "Right" and "Slow" signal combination is being displayed, and that when the handle is shifted forwardly and moved 30 downwardly that a "Right" and "Stop" signal is being displayed.

In order to prevent the escape of light 40 from the lamp 77 when illuminated, through the handle-accommodating pin 59 in the casing, it is proposed to provide on the handle a suitable guard or shield 97 which will properly co-operate with the opening to prevent the escape of a flood of light irrespective of the position of the handle.

The cover for the casing includes, in addition to the portion 82, an inclined portion 98, which overlies the angular extension 21 as 50 illustrated.

It is, of course, obvious that the controlling switch while shown and illustrated diagrammatically in connection with a particular form of device, is not intended to be limited to this form of device but is designed merely as a control for any form of traffic signal of the same general type as that set forth. The switch has been designed with a view to compactness, comparative simplicity of structure and the facility with which the same may be operated without materially distracting the attention of the driver of the vehicle from his ordinary duties. The indicating means forming a part 60 of the switch has been devised with a view

of adding to the general safety of the device in that the driver will always be aware and advised of the operating condition of the switch and the signals which are being controlled thereby.

70 What is claimed is:

1. A multiple switch, comprising a pair of bridge elements and a common operating member including sections pivotally connected for movement in planes at a right angle 75 to each other and each section carrying one of said bridge elements, whereby the movement in opposite directions of the operating member in either of said planes selectively bridges each pair of spaced contacts singly 80 and whereby movement in opposite directions of the operating member in both planes selectively bridges two of said pairs of contacts in combination.

2. A multiple switch including spaced 85 pairs of contacts, a pair of bridge elements and a common operating member including sections pivotally connected for movement in planes at right angles to each other and each section carrying one of said bridge 90 elements, whereby the movement in opposite directions of the operating member in either of said planes selectively bridges each pair of spaced contacts singly and whereby movement in opposite directions of the operating member in both planes selectively bridges two of said pairs of contacts in combination, and an indicating means 95 constituting a part of the switch, operable by the common operating member thereof.

3. A multiple switch, said switch comprising spaced pairs of contacts, a pair of bridge elements and a common operating member including sections pivotally connected for movement in planes at a right angle to each 105 other and each section carrying one of said bridge elements, whereby the movement in opposite directions of the operating member in either of said planes selectively bridges each pair of spaced contacts singly and whereby movement in opposite directions of the operating member in both planes selectively bridges two of said pairs of contacts in combination, and an indicating means constituting a part of the switch, operable by the 110 common operating member thereof.

4. A multiple switch, said switch comprising a common operating member including sections having pivotal connection for movement in planes at right angles to each other, and detent means for retaining said sections in their shifted positions.

5. A multiple switch including spaced 125 pairs of contacts for each of said devices,

130
